US00D749085S

(12) **United States Design Patent**
Furue et al.

(10) **Patent No.:** **US D749,085 S**
(45) **Date of Patent:** **** Feb. 9, 2016**

(54) **DISPLAY PANEL OR SCREEN WITH
GRAPHICAL USER INTERFACE**

(75) Inventors: **Nobuki Furue**, Tokyo (JP); **Ayaka Tamura**, Tokyo (JP); **Motoki Higashide**, Tokyo (JP)

(73) Assignee: **Sony Corporation**, Tokyo (JP)

(**) Term: **14 Years**

(21) Appl. No.: **29/371,960**

(22) Filed: **Feb. 23, 2012**

CLAIM

The ornamental design for a display panel or screen with a graphical user interface, as shown and described.

DESCRIPTION

FIGURE is a front elevational view of a display panel or screen with a graphical user interface showing our new design.

The broken line illustration of a camera and the display panel or screen thereof are included for the purpose of illustrating environmental structure and form no part of the claimed design.

1 Claim, 1 Drawing Sheet
